CLARENCE T. EVANS, OF WAUWATOSA, WISCONSIN, ASSIGNOR TO CUTLER-HAMMER, INC. OF MILWAUKEE, WISCONSIN, A CORPORATION OF DELAWARE

CONTROL SWITCH

Application filed October 28, 1929. Serial No. 402,938.

This invention relates to control switches, and is particularly applicable to pilot switches for controlling electric motors.

The invention has among its objects to provide an improved pilot switch which is operable by a shipper rod or rope and is adapted to control an electromagnetic line switch for an electric motor.

Another object is to provide a pilot switch of the aforesaid character including an operating element adapted upon a given unidirectional movement to make and break an operating circuit for the line switch and to insure establishment of a maintaining circuit for the line switch prior to interruption of the operating circuit therefor.

Another object is to provide a pilot switch of the aforesaid character including a simple, rugged and efficient switch operating mechanism including means for biasing the operating member into extreme positions.

Various other objects and advantages of the invention will hereinafter appear.

The accompanying drawings illustrate an embodiment of the invention which will now be described, it being understood that the embodiment illustrated is susceptible of modification without departing from the spirit and scope of the appended claims.

In the drawings,

Figure 1 is a plan view of a pilot switch embodying the invention, the cover of the enclosing casing therefor being removed and certain parts of the operating mechanism being broken away.

Figs. 2 and 3 are sectional views on lines 2-2 and 3-3 respectively of Fig. 1.

Figs. 4, 5 and 6 are side elevational views of the switch mechanism shown in Fig. 1 illustrating the same in different operating positions, and

Fig. 7 diagrammatically illustrates the circuit connections for the pilot switch.

Referring to the drawings, and more particularly to Figs. 1 and 2 thereof the pilot switch illustrated includes a movable contact element 1 associated with a terminal device 2 and adapted to cooperate with stationary contacts 3 and 4. Terminal device 2 and stationary contacts 3 and 4 are mounted

upon an insulating base 5 which is fixed to the rear wall of a box like enclosing casing 6 having a removable cover 7, and as herein-after set forth the contact element 1 is provided with an operating mechanism 8 which is carried by one of the side walls of said casing. 55

More specifically, contact element 1 comprises an elongated metal contact strip 9 having an insulating strip 10 fixed to the upper face thereof. Said contact element is provided with a pair of elliptical openings intermediate the ends thereof for receiving pins 11 and 12 fixed to base 5. Pin 11 is associated with terminal device 2, and as best shown in Fig. 3 said terminal device also includes a terminal plate 13 fixed to the front face of base 5 and a spring 14 surrounding pin 11 and held under compression between said terminal plate and strip 9 of contact element 1. As shown in Fig. 3 terminal plate 13 is provided with a binding post 13a. 60 65 70

In connection with the foregoing it should be noted that spring 14 tends to move contact element 1 outwardly upon pins 11 and 12 and also serves to electrically connect contact strip 9 with terminal plate 13. Also it should be noted that spring 14 provides a floating support for contact element 1 and permits translatory movement and also angular movement of said element in a plane coinciding with the axes of pins 11 and 12. 75 80

The stationary contacts 3 and 4 are arranged at opposite ends of bridging contact 1. Contact 3 cooperates with the underface of contact strip 9 and the same has a terminal plate 15 associated therewith which is fixed to the front face of base 5 and is provided with a binding post 15a. As shown in Fig. 3 stationary contact 4 comprises a C-shaped member having its lower leg secured to the front face of base 5. The lower leg of contact 4 is provided with a binding post 4a and the upper leg thereof cooperates with the upper face of contact strip 9. 85 90 95

The operating mechanism for bridging contact 1 includes a rotatable operating shaft 16 and a pair of L-shaped levers 17 and 18. Shaft 16 is rotatably mounted within a bearing member 19 fixed within an opening in one 100

of the side walls of casing 6. The outer end of shaft 16 has an operating lever 20 fixed thereto while the inner end of said shaft is fixed to one of the legs of lever 17. The other leg of lever 17 is arranged above contact element 1 and engages said element at a point intermediate terminal device 2 and stationary contact 4. Bearing member 19 is provided with a turned outer surface which forms a bearing for lever 18. Lever 18 has one of its legs rotatably mounted upon bearing member 19 and the other leg thereof is arranged above contact element 1 and engages the same at a point to the right of terminal device 2.

15 As shown in Fig. 2 levers 17 and 18 are provided with downwardly extending projections 17^a and 18^a, respectively, which are connected by a tension spring 21. Each of the extensions 17^a and 18^a is provided with a roller 22 and spring 21 is provided with hooked end portions for engaging said rollers. Rotation of lever 17 in opposite directions is limited by a pair of projections 17^b and 17^c thereon which cooperate with opposite sides of a fixed stop 23 secured to the rear wall of casing 6. Rotation of lever 18 in a counterclockwise direction is limited by a projection 18^b thereon which cooperates with the left side of stop 23.

30 The function and operation of the afore-described pilot switch will now be more fully described. Figure 2 illustrates the pilot switch in off position and as is apparent from this figure spring 21 tends to move lever 17 in a counterclockwise direction and lever 18 in a clockwise direction. Lever 17 is held against movement beyond the position shown in Fig. 2 by engagement of projection 17^b with stop 23 and in this position said lever holds contact element 1 out of engagement with stationary contact 4 against the action of spring 14. Also as is apparent from Fig. 2 lever 18 holds contact element 1 in engagement with stationary contact 3 against the 45 action of spring 14.

Upon movement of operating lever 20 from the off position shown in dotted lines in Fig. 2 to the intermediate position shown in dotted lines in Fig. 4, lever 17 is moved in a clockwise direction against the action of spring 21 to permit contact element 1 to move into engagement with stationary contact 4. With the operating parts in the position shown in Fig. 4 spring 21 biases lever 18 in a clockwise direction to hold contact element 1 in engagement with stationary contact 3 against the action of spring 14.

Upon movement of operating lever 20 in a clockwise direction slightly beyond the dotted line position shown in Fig. 4 lever 17 is moved to bring the axis of spring 21 above the center of operating shaft 16. Spring 21 then acts to bias lever 17 in a clockwise direction and lever 18 in a counterclockwise direc-

tion and the latter lever is moved with a snap action under the action of said spring from the position shown in Fig. 4 to the position shown in Fig. 5. As a result contact element 1 disengages stationary contact 3 with a snap movement under the action of spring 14. With the operating parts in the position shown in Fig. 5 contact element 1 is held in engagement with stationary contact 4 by spring 14 and levers 17 and 18 are held against movement under the action of spring 21 beyond the positions shown, by engagement of their associated projections 17^c and 18^b with stop 23.

During return movement of the operating lever 20 from the position shown in dotted lines in Fig. 5 to the intermediate position shown in Fig. 6 lever 18 remains in the position shown in Fig. 6 while lever 17 moves in a counterclockwise direction to disengage contact element 1 from stationary contact 4. Upon movement of operating lever 20 beyond the position shown in Fig. 6 to the position shown in Fig. 2 lever 17 is moved to bring the axis of spring 21 below the center of shaft 16. Lever 17 then moves with a snap action under the action of spring 21 and returns contact element 1 to the position shown in Fig. 2.

The above described pilot switch is connected as shown in Fig. 7 to control an electromagnetic line switch 24. Said line switch provides for connection of a motor M across a supply circuit indicated by line L¹—L² and the same is provided with an operating winding 24^a and normally open auxiliary contacts 24^b.

The pilot switch is shown in off position in Fig. 7 and as hereinbefore described during movement of operating lever 17 from the off position shown in Fig. 2 through the intermediate position shown in Fig. 4 contact element 1 engages contacts 3 and 4. The operating winding 24^a of the line switch is then connected across lines L¹—L² and said line switch in responding energizes the motor M and closes its auxiliary contacts 24^b. When the operating lever is moved to the on position shown in Fig. 5 contact element 1 disengages contact 3 and remains in engagement with contact 4 and the line switch is then maintained energized by a circuit extending through contact 4, contact element 1 and terminal device 2 of the pilot switch and through a resistance r and auxiliary contacts 24^b of said line switch. Return of the pilot switch to off position effects interruption of the maintaining circuit for the line switch without reestablishment of the operating circuit therefor. Under low voltage conditions the line switch 24 drops out and before the operating circuit for the line switch can be reestablished it is necessary to return the pilot switch to off position.

What I claim as new and desire to secure by Letters Patent is:

1. In a switching device, in combination, a movable contact element, a pair of stationary contacts associated with said element and located at opposite ends thereof, a spring associated with said element and tending to move the same into engagement with one of said stationary contacts and out of engagement with the other of said stationary contacts and operating mechanism for said contact element including an operating part movable unidirectionally to permit movement of said contact element into engagement with said former stationary contact while maintaining the same in engagement with said latter stationary contact and to thereafter permit movement of said contact element out of engagement with said latter stationary contact while maintaining the same in engagement with said former stationary contact. 70
2. In a switching device, in combination, a plurality of terminal contact members, a movable contact element adapted to cooperate therewith to selectively control two circuits, one of said contact members being permanently connected to said movable contact element, and operating means for said movable contact element including an operating part movable in one direction out of a given off position to first establish both of said circuits and to thereafter interrupt one of said circuits while maintaining the other, said operating part being returnable in an opposite direction to off position to interrupt said latter circuit without reestablishing said former circuit. 80
3. In a switching device, in combination, a movable contact element, a spring device associated with said element and tending to move the same in one direction, a pair of stationary contacts located at opposite ends of said element, and operating mechanism for said contact element including an operating part movable unidirectionally to permit movement of said contact element into engagement with one of said stationary contacts under the action of said spring device while maintaining the same in engagement with the other of said stationary contacts and to thereafter permit movement of said contact element out of engagement with said latter stationary contact with a snap action under the action of said spring device while maintaining the same in engagement with said former stationary contact. 90
4. In a control switch, in combination, a movable contact element, a terminal device therefor connected intermediate the ends thereof, a pair of stationary contacts located at opposite ends of said contact element and arranged on opposite sides thereof, and operating means for said contact element including a movable operating member, said operating means acting upon a given unidirectional movement of said operating member to first effect movement of said contact element into engagement with one of said stationary contacts while maintaining the same in engagement with the other of said stationary contacts, and to thereafter effect movement of said contact element out of engagement with said last mentioned contact while maintaining the same in engagement with said first mentioned contact. 95
5. In a control switch, in combination, a movable contact element, a spring terminal device for said element located intermediate the ends thereof and biasing the same in one direction, a pair of stationary contacts associated with said element and located on opposite sides thereof, a movable operating member, and operating connections between said operating member and said contact element which act upon movement of said operating member in one direction to first permit movement of said contact element into engagement with one of said stationary contacts under the action of said spring terminal device while maintaining the same in engagement with the other of said stationary contacts and to thereafter permit movement of said contact element out of engagement with said latter stationary contact under the action of said spring terminal device. 100
6. In a control switch, in combination, a movable contact element, a pair of stationary contacts located at opposite ends of said element and arranged on opposite sides thereof, a spring terminal device for said element located intermediate the ends thereof and biasing the same towards one of said stationary contacts and out of engagement with the other of said stationary contacts, a pivoted operating member operable between given extreme positions to effect movement of said contact element into and out of engagement with said first mentioned contact, and means associated with said lever and adapted to act upon movement thereof into its extreme positions to effect movement of said contact element into and out of engagement with said last mentioned stationary contact. 105
7. In a control switch, in combination, a movable contact element, a pair of stationary contacts located at opposite ends of said element and arranged on opposite sides thereof, a spring terminal device for said element tending to move the same into engagement with one of said stationary contacts and out of engagement with the other of said stationary contacts, a pivoted operating lever movable between given extreme positions to effect movement of said contact element into and out of engagement with said first mentioned contact, a second pivoted lever movable between given extreme positions for moving said contact element into and out of engagement with said last mentioned station- 110
- 120
- 125
- 130

ary contact and means for operating said latter lever with a snap action upon movement of said former lever in its extreme positions.

- 5 8. In a control switch, in combination, a movable contact element, a pair of stationary contacts located at opposite ends of said element and arranged on opposite sides thereof, a spring terminal device associated with
10 said element and biasing the same towards one of said stationary contacts and away from the other of said stationary contacts, a pivoted operating lever movable between given extreme positions to move said contact element into and out of engagement with said first mentioned stationary contact, a second pivoted operating lever movable between given extreme positions to move said contact element into and out of engagement with
15 said last mentioned stationary contact, and a spring connection between said levers providing for operation of said last mentioned lever with a snap action upon movement of said first mentioned lever into its opposite
20 extreme position and to yieldingly hold said first mentioned lever in such extreme positions.

In witness whereof, I have hereunto subscribed my name.

30 CLARENCE T. EVANS.
